(57) **CLAIM**

The ornamental design for a random orbital sander, random orbital sander mechanism and rotary sanding pad, as shown and described.

DESCRIPTION

FIG. 1 is a left side view of a random orbital sander, random orbital sander mechanism and rotary sanding pad showing my new design;

FIG. 2 is a front view of a random orbital sander, random orbital sander mechanism and rotary sanding pad;

FIG. 3 is a right side view of a random orbital sander, random orbital sander mechanism and rotary sanding pad;

FIG. 4 is a top view of a random orbital sander, random orbital sander mechanism and rotary sanding pad;

FIG. 5 is a back view of a random orbital sander, random orbital sander mechanism and rotary sanding pad;

FIG. 6 is an end view of a random orbital sander, random orbital sander mechanism and rotary sanding pad (showing attached sanding paper abrasive); and,

FIG. 7 is a right isometric view of a random orbital sander, random orbital sander mechanism and rotary sanding pad. The random orbital sander, random orbital sander mechanism and rotary sanding pad embodying the design is for shaping, sanding, and finishing contoured surfaces and can be an attachment for power saws such as angle grinders.
